UNITED STATES PATENT OFFICE.

MILEDEN WONSER, OF KINGSTON, KANSAS.

GRAIN-DRILL.

SPECIFICATION forming part of Letters Patent No. 337,543, dated March 9, 1886.

Application filed March 30, 1885. Serial No. 160,697. (No model.)

To all whom it may concern:

Be it known that I, MILEDEN WONSER, of 5
Kingston, in the county of Labette and State
of Kansas, have invented a new and useful Im-
provement in Grain-Drills, of which the fol-
lowing is a full, clear, and exact description.

Reference is to be had to the accompanying
drawings, forming a part of this specification,
in which similar letters of reference indicate
10 corresponding parts in all the figures.

Figure 1 is a plan view, partly in section, of
a part of a grain-drill, illustrating my invention.
Fig. 2 is a rear elevation of the same,
part being broken away. Fig. 3 is a sectional
15 end elevation of the same, part being broken
away. Fig. 4 is a transverse section of the
shaft and cutters, showing the manner of con-
structing the cutters; and Fig. 5 is a detail
section on line xx , Fig. 4.

20 The object of this invention is to provide
grain-drills constructed in such a manner that
they can be readily adjusted to deposit the
grain at any desired depth in the ground.

The invention relates to a grain-drill con-
25 structed with a frame and with a series of ro-
tary cutters mounted upon a shaft having a
series of inclined sections, and pivoted to bars
sliding in grooves in stationary bars, and con-
nected by ropes or chains and guide-pulleys
30 with a shaft pivoted to the said frame, where-
by the inclination of said cutters can be read-
ily adjusted and the said cutters can be read-
ily raised and lowered. The grain is delivered
at the sides of the rear parts of the rotary cut-
35 ters, in the channels opened by the said cutters,
by spouts supported by a bar attached to the
frame of the machine. The shaft carrying the ro-
tary cutters is made with inclined sections par-
allel with each other on each arm of the shaft,
40 and inclined in inverse directions on the two
arms of the shaft, as will be hereinafter fully
described and then claimed.

A represents the frame of the machine. To
the frame A are journaled the wheels B, upon
45 which the machine is carried.

To the inner sides of the side bars of the
frame A are attached vertical bars C, in the
inner sides of which are formed T-grooves to
receive the correspondingly-shaped sliding
50 bars D.

To the lower ends of the sliding bars D are

55 journaled the ends of the shaft E, which is
formed of a number of inclined sections. The
axes of the sections upon each side of the cen-
ter of the shaft E are parallel with each other
and at an angle with the axis of the shaft, and
the sections upon the opposite sides of the
center of the said shaft E incline in reverse
directions, as shown in Fig. 1.

Upon the inclined sections of the shaft E
60 are placed the hubs of circular cutters F,
which may be made convex upon their inner
sides and plane or slightly concave upon their
outer sides. With this construction the cut-
ters F upon each side of the center of the 65
shaft E will be parallel with each other, and
the cutters F, upon the opposite sides of
the center of the shaft E, will be at an
angle with each other, as shown in Figs.
1 and 2. With this construction, when the 70
shaft E is turned in its bearings, the inclina-
tion of the cutters F with respect to the surface
of the ground and the line of draft will be
changed, so that the said cutters will be ad-
justed to open wider or narrower channels by 75
turning the said shaft E.

In order to place the cutters on the shaft
they may be formed, as shown in Figs. 4 and
5, with a large central opening, f, and with
80 sectional boxes $f'f''$, fitted therein and secured
to the cutters by bolts, or in other suitable
manner.

In practice the cutters may be first slipped
on the shaft to the proper position, and the
box-sections be then applied. 85

To one end of the shaft E is attached a
square-toothed ratchet-wheel, G, with the teeth
of which engages the pawl H, pivoted to the
frame A or some other suitable support, so
that the shaft E can be readily adjusted and 90
will be held securely in any position into
which it may be turned.

To a cross-bar, I, attached to the frame A,
are attached the spouts J, by which the seed
is conducted from the seed-box into the chan- 95
nels opened in the soil by the cutters F. The
lower ends of the conducting-spouts J are
curved inward, so as to be nearly in contact
with the lower rear parts of the cutters F, and
thus introduce the seed into the channels 100
opened by the cutters F before the said chan-
nels have been partly filled by the falling in

of the soil at the sides of the said channels. The upper ends of the conducting-spouts J are flared to adapt them to better receive seed from the seed-box, which is not shown in the drawings, as there is nothing new in its construction or operation.

To the lower parts of the sliding bars D are attached the ends of ropes or chains K, which pass over guide-pulleys L, pivoted in slots in the upper parts of the flanges or supports M, formed upon or attached to the bars C in the T-grooves of which the said bars D slide.

To the upper parts of the sliding bars D are attached the ends of ropes or chains N, which pass around guide-pulleys O, pivoted in slots in the lower parts of the flanges or supports M. The other ends of the ropes or chains K N are wound in opposite directions around and are attached to the shaft P, which is pivoted to the frame A, so that by turning the said shaft P the sliding bars D will be raised or lowered to raise or lower the shaft E and cutters F, and thus adjust the said cutters to work at any desired depth in the ground. The shaft P can be turned by a lever inserted in holes in the said shaft, as indicated in dotted lines in Fig. 3, or by other suitable means. With this construction the machine will cut its way and clear itself in land fouled by stubble, weeds, cornstalks, or similar rubbish.

By the use of this machine the grain can be put into the ground with less draft-power than is required with ordinary drills.

Having thus fully described my invention, I claim as new and desire to secure by Letters Patent—

1. In a grain-drill, the combination, with the frame of the machine and a series of circular rotary cutters, of the shaft E, having inclined sections to receive the hubs of the said cutters, and a supporting and adjusting mechanism, substantially as herein shown and described, whereby the inclination of the said cutters can be readily adjusted, as set forth.

2. In a grain-drill, a shaft having a plurality of bearing-sections arranged at an angle to its axis, substantially as set forth.

3. In a grain-drill, the shaft E, made substantially as herein shown and described, with inclined sections parallel with each other on each arm of the shaft and inclined in reverse directions upon the two arms of the shaft, as set forth.

4. The combination of a rotarily-adjustable shaft having bearings arranged at an incline or angle to its axis of revolution, cutters journaled on said inclined bearings, and vertically-adjustable supports for said shaft, whereby the cutters may be set at any desired incline and held at a common depth with each position or inclination, substantially as set forth.

MILEDEN WONSER.
